UNDERGARMENT FOR WOMEN'S WEAR

Rosamond Lilian Kennedy, London, England

Application May 23, 1932, Serial No. 613,034
In Great Britain June 29, 1931

5 Claims. (Cl. 2—30)

This invention relates to undergarments for women's wear of the kind comprising at least two pieces or garments one of which may be a brassière or bust bodice designed to support the breasts and another body corset or belt. Other garments such for example as knickers may be combined with these two as desired.

According to the present invention a combination garment comprises one part provided with a flexible fastening device of the well known type comprising a pair of stringers having interlocking teeth or the like which are locked and unlocked by a slideable locking element (herein termed a slider) and another part connected to 15 the slider in such a manner that the action of donning the latter part of the garment automatically moves the slider to close the fastening device.

The invention may be applied in numerous ways 20 to various combinations of garments. One arrangement to which it may be applied very advantageously is that described in the specification of my application filed 29th July 1930 Serial No. 471,479 in which a bust bodice is provided 25 with a strap joining the outer ends of a pair of bust supports and passed through a loop on the upper edge of the back portion of a body belt or corset.

One way of applying the present invention to 30 this combination is hereinafter described with reference to the accompanying drawings, of which:—

Fig. 1 shows the combined garment as worn when viewed from the front.

35 Figs. 2 and 3 show the same as viewed from the back, the sliding fastening being open in Fig. 2 and closed in Fig. 3.

Fig. 4 is a fragmentary detail view showing the 40 sliding fastening as seen from the inner side of the garment.

Referring to the drawings:—

The combined garment comprises a corset A and breast pockets or supports B, B¹ which are joined in front to the corset at C. To the upper 45 corners of the breast pockets in front are attached shoulder straps D, D¹, said shoulder straps being attached at the back to the outer extremities G, G¹ of the pockets B, B¹. These outer extremities G, G¹ are joined by a connecting strap E provided with length adjusting devices H.

The corset A is provided at the back with a sliding fastening device of the well known type comprising toothed stringers F and a slider S. 50 The slider S is provided with a loop L through

which is passed the connecting strap E of the brassière.

In Fig. 2 the slider S is at the bottom of the fastening and the toothed stringers F are separated.

In Fig. 3 slider S has been drawn up to the top of the fastening device thus interlocking the toothed stringers.

To protect the wearer's back from chafing by the fastening device a strip K is provided on the 65 interior of the garment, said strip being provided with a hook M which can be engaged with eye N for securing strip K in place when the fastening is closed.

To don the combined garments the wearer first 70 puts on the corset A with the fastening F open and then places the bust bodice B, B¹ in position. When the shoulder straps D, D¹ of the bust bodice are placed over the shoulders as shown in Fig. 3 a pull is imparted through the connecting 75 strap E to the slider S which is thereupon drawn up to the top of the corset and closes the fastening.

In taking off the garments the hook M is first 80 detached from the eye N, the bust bodice is then removed and the corset fastening will then in most cases open by itself from the outward pressure of the body, or the slider may be pulled downwards by hand.

The fastening may be arranged at any other 85 part of the corset and a suitable connection made to the bust bodice such that the slider will operate on donning the bust bodice. It will further be apparent from the foregoing description that the invention may readily be applied to a variety 90 of combinations of garments.

What I claim is:—

1. A combination garment comprising a brassière including shoulder straps, a lower garment attached in front to said brassière, a slideable closure fastener for said lower garment and a connection between the brassière and the slideable closure fastener adapted to close the latter on placing the shoulder straps in position on the shoulders.

2. A combination garment comprising a brassière, shoulder straps therefor, a body belt attached in front to said brassière, a slideable closure fastener at the back of the body belt and connections between the rearward ends of the shoulder straps and the slideable closure fastener adapted to close the latter on placing the shoulder straps in position on the shoulders.

3. A combination garment comprising a brassière, shoulder straps therefor, a corset attached

to the brassière in front, a slidable closure fastener for said corset and connections between the rearward ends of the shoulder straps and the slid- able closure fastener adapted to close the latter on placing the shoulder straps in position on the shoulders.	80
4. A combination garment comprising a brassière, shoulder straps therefor, a corset attached to the brassière in front, a slidable closure fastener at the back of said corset and adjustable connections between the rearward ends of the shoulder straps of the brassière and the slidable closure fastener adapted to close the latter on placing the shoulder straps in position on the shoulders.	85
